UNITED STATES PATENT OFFICE.

NATHANIEL MARION CHANDLER, OF WOODLAND, CALIFORNIA.

SIPHON.

1,324,383.

Specification of Letters Patent.

Patented Dec. 9, 1919.

Application filed March 28, 1917. Serial No. 157,950.

To all whom it may concern:

Be it known that I, NATHANIEL M. CHANDLER, a citizen of the United States, and a resident of Woodland, in the county 5 of Yolo and State of California, have invented a new and useful Improvement in Siphons, of which the following is a specification.

My invention is an improvement in siphons and has for its object to provide a device of the character specified, especially 10 designed for use in transferring water from irrigating ditches to the fields to be irrigated, wherein a flexible tube is connected 15 with the delivery end of the siphon having a greater cross sectional area at its outlet than at its inlet, to decrease the velocity of the water, and to spread the discharging water in a flat sheet parallel with the 20 ground, to reduce the corroding effect of the water upon the land, and to provide means for stopping siphonic action when desired.

In the drawings:—

Figure 1 is a side view of the improved 25 siphon,

Fig. 2 is a partial vertical section at the delivery end,

Fig. 3 is a top plan view of the delivery 30 end showing the outlet in closed position.

In the present embodiment of the invention the rigid portion of the siphon consists 35 of a short leg 1, a long leg 2 and a connecting portion 3, and the rigid portion of the siphon is adapted to be arranged as shown in Fig. 1, with the short leg dipping into the water of the irrigating ditch 4, and with the long leg delivering onto the ground. The outlet for the long leg of the siphon 40 is a flexible tube 5 which increases in cross sectional area from the connected to the free end.

The small end of the tube is fitted over the end of the leg 3 of the siphon, and is held to the said leg by a band 6 of metal, the said 45 band engaging the siphon leg between annular ribs 7 on the siphon. Means is provided for cutting off the flow of water through the outlet 5 when desired, as for instance when removing leg 2 from the water, 50 said means comprising a loop 8 of flexible material which encircles the tube, and is passed through a ring 9 connected to the

band 6 by means of chains 10. The loop 8 is provided with an enlargement in the form of a knob or button 11 for preventing disengagement of the loop from the ring and for forming a handle for the loop.

In operation, when the siphon has been completely emersed in the liquid, the outlet end may be closed by pulling the loop 60 tightly as shown in Fig. 3, and the siphon will remain sealed and primed while being placed in position.

In addition, the weight of the water will tend to flatten the outlet tube as indicated in 65 Figs. 1 and 2, thus delivering the water in a thin sheet or layer. Because of the decreased velocity the carrying power or corroding effect of the water is greatly reduced and because of the spreading of the 70 water, the wash on the land is greatly reduced.

Moreover, the tube directs the water from the discharge in such manner that the water is well distributed and quickly. By pulling 75 the free end of the tube taut, the flow of the water may be quickly stopped and the suspending of the ring from the end of the metallic tube releases all strain from the flexible collapsible tube.

It will be noted from an inspection of Fig. 1 that the end of the leg 1 is beveled as indicated at 12 on a surface approximately parallel with the surface of the water, this arrangement preventing the formation of 85 eddies, whirlpools and the like in the water through which air is admitted to the siphon.

I claim:—

1. In combination with a siphon, a flexible collapsible tube having one end fitting around the effluent leg of the siphon and secured thereto, said tube increasing in cross sectional area toward its free end, in order to decrease the velocity of the water flow and to deliver the water in a sheet or layer 90 approximately parallel with the surface of the ground because of the tendency of the flexible tube to flatten on the ground, a handle comprising a flexible loop encircling the tube, a ring having a flexible connection 95 with the effluent leg through which the loop passes after encircling the tube, said loop having an enlargement to prevent displacement from the ring.

2. In combination with a siphon, a flexible collapsible tube having one end fitting around the effluent leg of the siphon and secured thereto, said tube increasing in cross
5 sectional area toward its free end, in order to decrease the velocity of the water flow and to deliver the water in a sheet or layer

approximately parallel with the surface of the ground because of the tendency of the flexible tube to flatten on the ground.

NATHANIEL MARION CHANDLER.
